LUMINAIRE OF THE WALL MOUNTED TYPE

Vearl S. Wince, Newark, Ohio, assignor to Holophane Company, Inc., New York, N. Y., a corporation of Delaware

Application August 16, 1949, Serial No. 4,521

Term of patent 14 years

(Cl. D48—4)

To all whom it may concern:

Be it known that I, Vearl S. Wince, a citizen of the United States of America and a resident of Newark, in the county of Licking and State of Ohio, have invented a new, original, and ornamental Design for a Luminaire of the Wall Mounted Type, of which the following is a specification, reference being had to the accompanying drawing, forming a part hereof.

In the drawing:

Figure 1 is a perspective view of a luminaire of the wall mounted type, showing my new design; Figure 2 is a front elevational view thereof; Figure 3 is an end elevational view; and

Figure 4 is a top plan view, the inverted plan being the same as the top plan.

I claim:

The ornamental design for a luminaire of the wall mounted type, as shown and described.

VEARL S. WINCE.
